COMBINED HANGER AND BRACKET

William J. Thompson, 1414 8th St., Wichita Falls, Tex.

Filed Sept. 16, 1964, Ser. No. 31,745

Term of patent 7 years

(Cl. D17—12)

FIG. 1 is a perspective view of a combined hanger and bracket showing my new design; and

FIG. 2 is a side elevational view of the combined hanger and bracket.

The back thereof is substantially plain.

I claim:

The ornamental design for a combined hanger and bracket, as shown and described.
